(57) **CLAIM**

The ornamental design for a personal microdermabrasion device, as shown and described.

DESCRIPTION

FIG. 1 is a perspective view of the personal microdermabrasion device, looking towards a front of the face. The upper portion of the handle is rotatable, and is illustrated in a first position.

FIG. 2 is a first side view of the personal microdermabrasion device, looking at a power switch. The upper portion of the handle is in the first position.

FIG. 3 is a second side view of the personal microdermabrasion device showing a latch button, the side view taken 180° opposite to the first side view shown in FIG. 2. The upper portion of the handle is in the first position.

FIG. 4 is a third side view of the personal microdermabrasion device taken 90° to tile first side view shown in FIG. 2. The upper portion of the handle is in the first position. The fourth and opposite side being a mirror image.

FIG. 5 is a first end view of the personal microdermabrasion device.

FIG. 6 is another view of the third side, wherein the upper portion of the handle is in a second position rotated around about 180° from the first position; and,

FIG. 7 is a perspective view of the personal microdermabrasion device.

The broken line showing of abrasion heads represent unclaimed environment and form no part of the claimed design.
